CLAIM

The ornamental design for an ottoman, as shown and described.

DESCRIPTION

FIGS. 1-3 show the ottoman. From the top view, this embodiment is generally square in shape.

FIG. 1 is a perspective view of the ottoman showing two sides and the top of the invention.

FIG. 2 is a top view thereof; and,

FIG. 3 is a side view of the ottoman, the other side views being identical thereto.

In each Figure, all surfaces not shown form no part of the claimed design.
